CLAIM

The ornamental design for a shower head as shown and described.

DESCRIPTION

FIG. 1 is a front perspective view showing of a shower head showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged partial view of a portion indicated with letter A in FIG. 1.

The broken lines in the figures illustrate nozzles of the shower head that form no part of the claimed design, and the dashed lines in FIG. 1 and FIG. 8 are for the purpose of depicting the boundary lines of the enlarged view and form no part of the claimed design.
